UNITED STATES PATENT OFFICE.

CHARLES E. GODLEY, OF DETROIT, MICHIGAN, ASSIGNOR, BY MESNE ASSIGNMENTS,
TO C. M. HALL LAMP COMPANY, A CORPORATION OF MICHIGAN.

HEADLAMP CONSTRUCTION.

Application filed October 5, 1925. Serial No. 60,643.

My invention relates to lamp constructions and in most of its features to the providing of a lamp casing having a detachable portion which is adapted to be removed for affording access to the interior of the casing without disturbing the lens-carrying lamp front. For this purpose, my invention provides a lamp casing composed mainly of two parts adjoined along a medial longitudinal plane of the lamp and having one of these parts detachable to afford access to the interior of the casing.

More particularly, my invention provides a casing construction of this class which can readily be made of sheet material, and provides a joint construction which will insure a tight closure between the stationary casing part and the detachable casing portion, and which will prevent a relative shifting or spreading of these parts. My invention also provides novel and effective means for latching the detachable casing portion in its normal position. Furthermore, my invention provides novel means carried by one of the casing portions for resisting the thrusts of a spring which holds a reflector in operative position within the casing. Still further and also more detailed objects will appear from the following specification and from the accompanying drawings, in which

Fig. 1 is a side elevation of a headlight having a casing or body embodying my invention.

Fig. 2 is an enlarged central, vertical and longitudinal section through the same lamp.

Fig. 3 is an enlargement of the upper right hand portion of Fig. 2.

Fig. 4 is an enlargement of the rear portion of Fig. 2.

Fig. 5 is a perspective view of the rockingly mounted latching member which normally holds the detachable casing portion in its closure position.

Fig. 6 is a fragmentary view similar to a portion of Fig. 4 but showing the latch in its released position.

Fig. 7 is a transverse vertical section taken along the line 7—7 of Fig. 2 but drawn on a larger scale than Fig. 2.

Fig. 8 is an enlarged perspective view of the thrust member which is mounted on a stationary casing portion and which resists the thrust of the reflector-holding spring.

Fig. 9 is a central and longitudinal sec-

tion through the two casing parts alone, showing the fingers which interlock these parts against relative sliding or spreading.

Fig. 10 is a plan view of the lower casing part alone, before the needed perforations are formed in it.

Fig. 11 is an enlarged and fragmentary vertical section taken along the line 11—11 in Fig. 10.

Fig. 12 is an enlarged vertical section taken along the line 12—12 of Fig. 9.

In one of its immediate commercial applications, my invention is particularly suitable for use in connection with lamps having elliptical reflectors such as the headlamp shown in my copending application No. 751,255, filed November 21, 1924 on a headlight construction. In this lamp, the reflector is ovoid and composed of two metal parts disposed one behind the other, the forward part being stationary and the rear part being pressed by a spring into its normal position, access being afforded to the interior of the reflector and to the lamp bulb within the reflector by separating the rear reflector portion from the forward or stationary reflector portion.

To permit access to the rear reflector portion for this purpose, and also to the socket-focusing means employed in connection with the lamp bulb, it is important that a suitable part of the casing should be conveniently removable. In one of its immediate aspects, my invention provides a casing or body particularly suited to this purpose and also provides other features which are advantageous in lamp constructions employing split casings.

Referring first to Fig. 1, this shows the exterior of the lamp as including upper and lower semi-ovoidal casing or body halves, each of which is cut off at its forward end and adjoined to a front lens ring 3 which carries the glass lens 4 of the lamp. This figure also shows the head of the latch releasing screw 20 and one of the rivets 6 which secure a spring-thrust receiving member to the lower or stationary half of the casing.

To insure a weathertight and dust-tight seal between the two casing portions, each of which can be formed of sheet metal, I provide the upper part 1 with an inwardly extending ledge 8 which desirably is disposed substantially in a horizontal plane 110

medial and longitudinal of the lamp, and provide the lower portion at its upper edge with an inwardly directed flange or ledge 9 upon which the aforesaid flange 8 seats. 5 These flanges 8 and 9 desirably extend around the rear end of the corresponding casing part and along the sides of each part for the full length of each casing half, but not across the front or cut-off portion of 10 that part.

I also provide at least one, and desirably both, of these flanges with fingers which hook over the edge of the other flange, these fingers being preferably disposed unsymmetrically at opposite sides of the vertical medial plane of the casing so that the same die can be used for blanking both parts of the casing. Thus Fig. 10 shows the partially completed lower casing part as having 20 five spaced riser fingers 10 extending upwardly from the inner edge of the flange 8 at each side of the center line. With the upper casing part similarly blanked and formed, the corresponding fingers 40 on the 25 latter project downwardly between the fingers 10 on the lower part, as shown in Figs. 9 and 11, when the parts are rejoined. When the casing is thus closed, the riser fingers 10 prevent an inward movement of 30 the flange 9 on the upper casing half and an outward movement of the flange 8 on the lower casing half, while the depending fingers 40 prevent movements of these flanges in the opposite directions. Hence 35 this simple finger arrangement prevents each casing part from being flattened by vertical pressure on it, thereby insuring the desired rigidity even when these parts are made of rather thin metal. The fingers 10 and 40 likewise prevent each casing part 40 from sliding on the other transversely of the lamp, thereby cooperating with the hereafter described interfitting of the forward casing end with the lens ring, and 45 with the latter described interlatching of the rear ends of the casing parts, in affording a rigid casing.

At its front, the lower casing part 2 is formed to afford a substantially vertical annular flange 11 adapted to be secured by a 50 pair of screws 12 to the lens ring 3 so as to hold this lens ring stationary with respect to the lower casing part 2, this lower part being fastened to a bracket 36 which 55 may be secured to any suitable support by means of a bolt 13. Then I provide the upper casing part 1 at its forward end with a generally vertical annular flange 14 having a semi-annular offset 15 which is normally telescoped into a correspondingly shaped rear end portion of the lens ring as shown in Fig. 3.

With the two casing parts and the lens ring thus constructed, the flange 8 of the 60 upper casing part seats on the flange 9

of the lower casing part and the telescopic interfitting of the lens ring with the front of the upper casing part holds the forward portion of the latter in its normal position. 70 To secure the rear portion of the upper casing part also in its normal position, I provide means releasable from outside the casing for latching the rear ends of the two casing parts to each other. For that purpose I am here showing a latch pivoted at 75 its upper end 16 to the upper casing part and having its lower end 17 normally underhanging the inner edge of the rear portion of the flange 9 on the lower casing part. 80 As a convenient means for pivotally securing this latching member to the upper casing portion, I provide a pivot plate 18 which bears against the said casing part and which is pressed against the latter by a spring 19 interposed between the pivot 85 plate and the latching member. Both the pivot plate and the latching member are perforated so that a screw 20 can extend freely through them into a nut 21 bearing against the forward face of the latching member, and the latching member has a side ledge 41 (Fig. 5) which engages the nut 21 to keep the latter from rotating. 90 This screw desirably has a forwardly tapering head rotatably socketed in a corresponding tapering depression 22 in the upper casing half, the bore of the socketing portion being sufficiently great to permit the screw to tilt with respect to the lamp body. The upper end of the pivot plate desirably is 100 formed into a hook which engages the recurved upper end 16 of the latching member, while the lower end of the pivot plate seats on the flange 8 of the upper casing part so as to prevent the pivot plate from 105 rotating.

With the latch thus arranged, a tightening of the screw 20 will swing the latching member rearwardly about its pivotal engagement with the pivot plate 18, so as to 110 force the lower end 17 of the latching member against the inner edge of the flange 9, thereby drawing the upper casing part downwardly and forcing the rear end of this casing part into firm engagement with the lower casing part. When the screw 20 is relaxed, the compression spring 19 swings the latching member forwardly as shown in Fig. 6, thereby permitting the lower end of the latter to clear the flange 9, 115 so that the upper casing part can be raised at its rear end. Then the upper casing part can be drawn rearwardly until the offset 15 at the forward end of the upper casing part clears the lens ring, after which this upper casing part can be lifted off.

With the upper casing part removed, access is afforded to the focusing device 23 as employed in connection with the socket 24 for the lamp bulb 25, this focusing de- 130

vice being here shown in the type disclosed in my copending application No. 250,810 filed April 22, 1925. Access is also provided to the reflector, so that the rear portion 26 of the latter can be detached from the forward portion 27 which is secured to the lens ring by screws 12'.

The two reflector parts as here shown also have telescopically interfitting flanges 10 at their adjacent ends, and the rear reflector portion is continuously pressed forward and into its said interfitting relation to the forward reflector portion by a spring 29, after the general manner disclosed in my 15 said copending application No. 751,255.

In this last mentioned application, I showed such a spring as bearing directly against the inner end of the casing, which is quite feasible when the casing or body is 20 made of castings. In employing sheet metal for parts of a similar lamp body, the metal which must be employed to permit a shape like the illustrated one to be formed from it must be so thin that an adequate bearing of the spring directly against the metal would be apt to distort the latter. For this reason, I preferably interpose a 25 thrust-receiving member between the spring and the rear end portion of the lower or stationary casing part 2. This member has 30 a main or riser portion 30 which desirably has its upper end formed with a recess 31 in which the rearwardly bowed rear end of the spring seats, and has a foot portion 32 secured to the lower casing part by rivets 35 6. It also desirably has a thrust finger 33 formed from it and extending rearwardly into engagement with the lower casing part, so that this thrust finger will prevent the 40 thrust member from rocking about its riveted foot and will cooperate with the said foot in distributing the pressure of the spring over so large a portion of the lower casing part as to prevent the latter from 45 being bent out of shape.

The two casing parts 1 and 2 may obviously be made of various metals and suitably plated or otherwise finished, so that my construction lends itself to the producing of handsome casings which also are 50 relatively inexpensive in manufacture after the dies have been made. However, while I have illustrated and described my invention in an embodiment including various 55 highly desirable details of construction and arrangement, I do not wish to be limited as to these, it being obvious that many changes might be made without departing either from the spirit of my invention or 60 from the appended claims.

I claim as my invention:

1. A lamp body comprising a pair of sheet metal parts adjoined along a medial plane longitudinal of the lamp, and a lens-carrying front secured to one of the parts

and slidably entered by the forward end portion of the other part; one of the said parts having an inwardly directed flange substantially in the said plane, on which flange the other part normally seats and is adapted to slide during the attaching and detaching of the said other part; the said parts having spaced pluralities of integral interengaging portions cooperating with the said entry of a forward end portion into 70 the lens-carrying front for normally affording the sole means to prevent a relative shifting of the said parts transversely of the lamp.

2. A lamp body comprising a pair of 80 sheet metal parts adjoined along a substantially medial plane longitudinal of the lamp, each of the said parts having an inwardly directed flange presenting a face in that plane and having spaced fingers extending from the inner edge of the said flange past the inner edge of the flange on the other part, the flanges on the two parts resting normally on each other, the fingers on the two parts being in staggered relation to each other; in combination with a lens-ring fitted over the forward ends of the 85 said body parts, and releasable means for securing the rear ends of the said body parts to each other. 90

3. A lamp casing comprising a pair of body halves adjoined in a plane substantially diametric of the casing, and a lens ring fitting the forward ends of both body halves; the said body halves having flanges 100 extending inwardly of the casing and normally resting on each other, and having interengaging portions spaced from the forward ends of the said halves for preventing relative lateral shifting of the said half; and a latching member movably mounted on one of the said halves and normally engaging the flange on the other half to clamp the rear ends of the said halves 105 to each other. 110

4. In a lamp, the combination with a pair of interfitting casing halves one of which has a forwardly directed flange at its rear end, of means fast on the other casing half and releasably engaged with the first named casing half for holding the two halves adjoined at their forward ends, a latching member pivoted to the first named casing half within and at the rear end thereof and normally engaging the said flange to secure the casing halves to each other, a spring continuously tending to rock the latching member out of its said flange-engaging disposition, and threaded means operable from outside the casing for moving the latching member into its said disposition against the resistance of the spring. 115

5. The combination with a pair of adjoined lamp casing parts of a pivoting member disposed within one of the said 120 125 130

parts adjacent to the juncture of said parts, the pivoting member having an edge portion spaced from the casing part within which it is disposed; a latching member manually attachable to the pivoting member and having a portion hooked over the said edge portion to pivot the latching member on the pivoting member, the latching member having a perforation; threaded means interposed between the last named casing part and the latching member for swinging the latching member into a position in which a portion of the latter underhangs a part of the other casing part, the threaded means including a member extending through the said perforation and serving to hold the said portion of the latching member hooked over the said edge portion of the pivoting member, and spring means for urging the latching member in the opposite direction.

6. The combination with two adjoined lamp casing parts having relatively overlapping and inwardly directed flanges at their junctures, of a pivoting member disposed within and bearing flatwise against one of the parts and with one edge in engagement with the flange on that part; a latching member pivotally mounted on the pivoting member and having a portion normally underhanging the flange on the other casing part; spring means continuously tending to swing the latching member about its pivotal mounting and out of its said flange underhanging disposition, and threaded means interposed between the first named casing part and the latching member and operable from the exterior of the casing for moving the latching member in the opposite direction; the threaded means and the spring serving as the sole means for securing the pivoting member to the first named casing part.

7. The combination with a pair of adjoined lamp casing parts one of which has

a perforation adjacent to the juncture of the said parts, of a screw extending through the said perforation and adapted to rock about the casing part having the perforation, a latching member pivotally connected at one end on the last named casing part and having its other end adapted to engage a portion of the other casing part so as to draw the two casing parts toward each other, a nut rockingly engaging the inward face of the latching member and threaded upon the screw, and a spring operatively interposed between the first named casing half and the latching member and continuously urging the latching member out of its said engaging disposition; the latching member having a wing directed inwardly of the casing and engaging the nut to prevent rotation of the nut.

8. In a lamp, the combination with an ovoid reflector having an apertured forward end, of a housing for the reflector and having its forward end in engagement with the reflector, the housing including a pair of parts adjoined substantially in a central longitudinal plane of the reflector, releasable means for securing the said parts to each other, a thrust-receiving member fast on one of the said parts, and a spring fast on the rear end of the reflector and in releasable engagement with the thrust-receiving member and disposed for forcing the reflector forwardly.

9. A lamp construction as per claim 8, in which the thrust-receiving member is secured at one end to one of the housing parts and has its spring-engaging portion at its other end, and in which the said member has a brace extending from an intermediate portion of the said member into engagement with the last named housing part.

Signed at Detroit, Michigan, September 24, 1925.

CHARLES E. GODLEY.
